CUTTING DEVICE

August J. Lurie, Chicago, Ill.

Application August 23, 1940, Serial No. 353,879

7 Claims. (Cl. 30—333)

The present invention relates in general to a knife or cutting device and more particularly to such devices as employ safety razor blades or the like for a cutting or scraping operation.

In the prior combination cutting and scraping devices employing a razor blade or the like, difficulty is encountered in quickly moving the blade from one adjusted position to another. Furthermore, the devices have been such, in many instances, that the blade will not stay in an adjusted cutting or scraping position when under heavy operating pressure. In addition, there is the ever-present danger in some of the prior devices of cutting the operator during use, or during adjustment.

One of the objects of the present invention is to provide a simple and efficient cutting device or scraper employing a razor blade in which the cutting edge is protected when not in use.

Another object is to provide a device of this character in which the blade has two positions—a retracted position and a working position.

Another object is to provide positive means spaced from the cutting edge of the blade for moving the cutting blade from one position to the other thereby eliminating any possibility of cutting one's self in the operation.

A further object is to provide a device of this character for positively locking the blade in either position.

Still another object is to provide a sturdy, simple, and inexpensive cutting and scraping device.

There are other objects of my invention which, together with the foregoing, will appear in the detailed description that is to follow, taken in conjunction with the accompanying drawing illustrating one embodiment thereof.

In practicing my invention I employ a metal handle which may be cast or stamped to the desired shape, and the end of the handle is so shaped as to furnish a guide or channel in which a blade slides from retracted to operating position.

Fig. 1 is a top plan view of my improved cutting device or scraper showing the blade in extended position;

Fig. 2 is a bottom plan of the same device;

Fig. 3 is a fragmentary enlarged section taken along the line 3—3 of Fig. 2, looking in the direction of the arrows; and

Fig. 4 is an enlarged end elevation of the device showing the manner in which the blade is guided.

Referring now to Fig. 1 of the drawing, the

reference character 5 designates the handle which is cast or stamped from any suitable metal in the shape shown. A knife or blade guide 6 rectangularly shaped is formed integrally with the handle 5 and is provided with upwardly extending flange portions along opposite sides thereof. The blade guide 6 is of suitable width to receive a blade 8 which may be the usual safety razor blade, although other blades of a similar size and shape are equally suitable. The blade guide 6 is provided with a rectangular slot 9 which length determines the travel of the blade 8 from retracted to operative position.

A pair of depressions 10 and 11 are formed 15 on either side of the blade guide 6 suitably spaced to determine the travel of the blade 8 from retracted to operative position, and cooperate in maintaining a blade in either of the two adjusted positions. A substantially rectangularly shaped blade holder 12 is formed from suitable metal and is provided with upstanding flanges 13 cooperating with the flanges 7 of the blade guide 6. The holder 12 is provided with a pair of depressed lugs 14 adapted to penetrate 20 the depressions 10 and 11 and so lock the blade in one of two positions.

The blade holder 12 is provided with a rectangularly shaped opening 15 (Fig. 1) adapted to receive the rectangularly shaped shank of a 25 screw 16 which fastens the blade 8 in position in the holder 12 and penetrates the adjusting slot 9 in the blade guide 6. The screw 16 is provided with a rounded head 17 and a knurled adjusting nut 18 which may be easily and conveniently grasped by an operator adjusting the position of the blade.

The device is assembled by placing the screw 16 in the slot 9, then putting the blade 8 in position in the blade guide, followed by the blade holder 12 positioned upon one face of the blade, and the adjusting nut 18 on the screw 16. Loosening the adjusting nut permits the blade to be moved from retracted to operative position, where tightening of the nut 18 causes the lugs 30 45 50 55 14 to be tightly clasped into either of the depressions 10 and 11, thus locking the blade in one of two positions. Of course, the blade 8 may be adjusted to a position between these two, if necessary, though in such an instance it is only held frictionally and not positively locked.

It will be seen that my device permits easy movement of the blade from retracted to operative position with a positive guide from one position to the other, with no danger of the operator being cut in such manipulation. This device

may be used in the customary manner for a scraper, knife, box opener, etc., and a sturdy tool is assured under all conditions.

It will be seen that my improved device is simple, inexpensive to construct, and highly efficient in operation.

My invention may be variously modified without departing from the spirit and scope thereof as indicated in the appended claims.

I claim:

1. A cutting device having a handle, a substantially rectangularly shaped blade guide formed integrally with said handle having an upstanding flange along each of two opposite sides thereof forming a guiding channel, a blade holder adapted to slide in said channel, a blade in said guiding channel intermediate said blade guide and blade holder and movable with said holder to a cutting and to a non-cutting position, means for clamping said holder to said guide with the blade retained therebetween, and means for determining at least two clamping positions for said holder.

2. A cutting device having a handle, a rectangularly shaped blade guide portion with a blade thereon having parallel upstanding flanges severally along both sides thereof extending in the direction of movement of said blade on said portion and forming a guiding channel, a rectangular slot in said blade guide parallel to said upstanding flanges, a screw with a rectangular shank penetrating said slot adapted to carry a blade fitting in said channel, said blade being carried in said channel and having an aperture receiving said screw, and with said blade being movable in said channel with said screw to at least a cutting and to a non-cutting position, and a nut on said screw and operatively connected with said blade for clamping said blade in said channel in either a cutting or a non-cutting position.

3. A cutting device including a handle and a blade carrying portion, said blade carrying portion having a plurality of depressions therein spaced apart from one another in the direction of movement of a blade on said portion, a blade carried on said portion, and clamping means on said blade oppositely disposed thereon with reference to said portion having extending means thereon selectively fitting into one of said depressions upon movement of said clamping means, and assembly means operatively connecting said blade and clamping means together and extending through both for maintaining said clamping means and the blade therewith in any one of a plurality of adjusted positions with said extending means fitting in one of said depressions at an adjusted position.

4. In a device as defined in claim 3, said blade carrying portion having an upstanding flange on each of two opposite edges thereof extending in

the direction of movement of said blade and forming a guide channel thereon, and guide means on corresponding edges of said clamping means engaging said flanges to maintain said clamping means and the blade therewith in said channel.

5. In a device of the character described, a one-piece handle and blade carrying member having a handle portion at one end thereof and a blade carrying portion at the other end thereof, a blade carried on said blade carrying portion, a blade holder positioned on said blade, assembly means extending through said blade holder, blade and blade carrying portion for maintaining said blade and holder and member in assembled condition, a pair of depressions in said blade carrying portion defining two adjusted positions of said blade, and lug means on said blade holder engaging one or the other of said depressions depending upon the adjusted position of said blade with reference to said blade carrying portion, and cooperating guide means on said blade carrying portion and said blade holder to guide the blade holder and the blade therewith in a single channel extending longitudinally with reference to the handle portion of said member.

6. A cutting device including in combination a handle, a blade carrying portion operatively connected therewith, a movable blade holding portion, a blade on said blade carrying portion movable with said blade holding portion and positioned intermediate said two portions, and means clamping said two portions and said blade together in any one of at least two adjusted positions, with one of said portions having projecting means thereon, and the other of said portions having a recess therein corresponding to each adjusted position for receiving said projecting means and acting to define the adjusted positions of said blade and said blade holding portion and acting with said clamping means to maintain an adjusted position for said blade and blade holding portion.

7. A cutting device having a handle, a guide portion thereon having an upstanding flange along one side thereof, a blade holder for holding a blade and having a flange cooperating with that of the guide portion and together with said blade adapted for sliding movement to at least a cutting and a non-cutting position for said blade on said guide portion, said blade being positioned intermediate said guide portion and the blade holder, with said cooperating flanges acting to guide said blade holder when it is moved and cooperating to retain said blade against turning when it is in cutting position, cooperating means on said guide portion and said blade holder defining said two blade positions, and clamping means for said blade and blade holder.
